UNITED STATES PATENT OFFICE.

GEORGE HOLT FRASER, OF NEW YORK, N. Y.

SCREENING APPARATUS.

1,202,374.

Specification of Letters Patent. Patented Oct. 24, 1916.

Application filed June 15, 1906, Serial No. 321,856. Renewed December 27, 1915. Serial No. 68,919.

To all whom it may concern:

Be it known that I, GEORGE HOLT FRASER, a citizen of the United States, residing in the borough of Brooklyn, county of Kings, city and State of New York, have invented certain new and useful Improvements in Screening Apparatus, of which the following is a specification.

This invention relates to screening apparatus, and especially to apparatus of this character in which the material to be screened or sized is allowed to flow down an inclined screen through which the smaller particles fall to a fines outlet, and over which the larger particles flow to a coarse or tailing outlet. Apparatuses of this kind are used with one or more inclined screens, either stationary, vibrated, or jarred, inclosed in a casing, and used with a distributor for spreading the material to be screened over the upper part of the screen.

My invention aims to provide various improvements in apparatus of this general character, which will be hereinafter more fully set forth with reference to the accompanying drawings, in which—

Figure 1 is an end elevation showing the preferred form of my invention; Fig. 2 is a rear elevation thereof partly in vertical longitudinal section on the line 2—2 in Fig. 1, and looking in the direction of the arrow; Fig. 3 is a vertical cross-section thereof cut on the line 3—3 in Fig. 2 and looking in the direction of the arrow, and partly broken away; Fig. 4 is a fragmentary cross-section thereof cut on the line 4—4 in Fig. 1 and looking in the direction of the arrow; Fig. 5 is a cross-section thereof cut on the line 5—5 in Fig. 1 and looking in the direction of the arrow. Fig. 6 is an enlarged fragmentary section of the body cut on the line 6—6 of Fig. 7 and looking in the direction of the arrow; Fig. 7 is an enlarged fragmentary section thereof cut on the line 7—7 in Fig. 6 and looking in the direction of the arrow. Fig. 8 is a fragmentary vertical section looking from the rear and showing the distributor reversed, and Fig. 9 is a vertical cross section showing a modification.

Referring to the drawings, A is the main body, B are its feet, C are its legs, D is the feeder body, E is the hopper, and F is the

driving shaft. Within the body A is a screening member G, beneath which is the fines outlet H, and in front of the lower end of which is the coarse outlet I. At the top of the screen is the inlet J, above which is a conveyer or other distributing feeder K. The material entering through the hopper E is distributed by the conveyer K throughout the length of the inlet J, from which it flows on to the screen G, down which it runs, the fines falling through and escaping through the fine outlet H and the coarse flowing down and passing out of the coarse outlet I.

As thus far described the parts may be of any usual or suitable construction.

According to the preferred form of my invention, I provide an improved construction for the main body A, the feeder D, the screening member, and an improved vibrating mechanism L, and I provide various details of improvement in construction, arrangement and operation, all of which will be more fully hereinafter set forth.

The body A consists of a tubular casing of substantially rectangular cross-section, closed at front by a front door a, which slides or is adjustable vertically in grooves formed in the body, and at rear by a hinged rear door b, which body has an open top beneath the feeder, and an open bottom at its front end for the outlets, and is pivotally mounted on its feet B at front by pins c or otherwise, and adjustably connected to the legs C by pins d or otherwise, so that the angle of the body can be set at the degree of inclination desired. The body A is preferably composed of two identical ends e of cast or other metal, united at their lower front part by a cross-piece or angle bar f, at the lower part of their rear ends by a bar g, at top by a cross-piece or angle bar h at rear and i at front, and at their lower front end by a cross-piece or angle bar j, which connections preserve the two sides in suitable relation. The top and bottom sides of the main casing are preferably both closed by removable walls or covers, the top by sheet metal covers l which have edges reinforced by angle irons m at bottom, and by Z-bars n at top, which are fitted together at their edges to hold the covers in place and prevent leakage of dust. Another Z-bar n is carried by the casing below the

vers, and above the covers a corresponding angle bar *o* is carried by the casing, to which bars the adjacent edges of the covers are fitted. By this construction any cover 5 may be easily removed to get access to the screen member from in front. At each end each cover is also clamped by a swinging clamp *p* pivoted to the end wall *e*.

The bottom of the main body is a movable or removable door *M* according to my 10 invention, and preferably consists of a metallic frame *N* composed of upwardly extending angle bars *q* connected at top by a T-bar *r* and at bottom by an angle bar *s*, and carrying a sheet metal covering *v* and *w* closing the rear or bottom wall of the body. The door *M* preferably fits within the end 15 walls and is pivoted thereto near its lower end by the pin *t* so that its upper end can be swung downwardly to give access to the 20 interior from the rear. It makes suitably tight connection with the end walls by contact of its frame with the shoulder *u* therein, and with the bar *g* by contact of the bar *r* 25 therewith, and it is held in the closed position in any suitable manner, as by the gravity clamps *p* with which the top and bottom edges of the ends *e* are provided. The outer face of each end *e* is cast with a flange *x* 30 fitting against the inner face of the feet *B* at the lower end, and the inner face of the leg *C* at the upper end, and with lugs *y* for connecting the feeder to these ends, and with ears *z* for carrying the clamps.

The screen member *G* is preferably 35 mounted on the movable back *M* so that it can be removed or lowered with this back for giving access to the screens. It may be mounted directly on the frame *N* but I prefer to support it movably or resiliently 40 thereto by a yielding or electrically or resiliently mounted frame *P* carried from the frame *N* by elastic or resilient springs *Q*, and I prefer to provide a plurality of screen members 45 separately connected to the frame *P*, as by sliding them thereto from the rear end, so that any one may be removed for repair either by sliding it out rearwardly without lowering the back door, or by low 50 ing this door and then sliding it out, or by removing its clamps *R* and lifting it out. As shown, the springs *Q* are disposed in transverse rows between and spaced intermediate of the sides of the casing, and are 55 under the longitudinal edges of the rectangular frames on which the screen cloth ing is stretched. And resiliently support adjacent edges of interior screens, and a number of channel bars *a'* are carried by the 60 frame *N*, and the springs *Q* are mounted on these and on the end angles *q*, and the frame *P* consists of a number of inverted channel bars *b'* embracing the upper ends of the springs and having their ends connected by angle bars *O* embracing pest *c'* at

the top and bottom of the bars *a'* for slidingly supporting the screen frame. The clamps *R* between the screen members *G* are shown as each consisting of a straight bar *e'* of strap iron connected to the frame *P* by a bolt *f'*, 70 and over each bar *k* the clamp consists of an inverted angle iron *g'*. The bolts *f'* may go through the leaf springs *Q*, to retain these in place. The upper end of each screen member *G* has a downwardly projecting portion *h'* which hangs on the screen frame *P*. 75

The screen may be sufficiently resilient to be moved, jolted or vibrated in any usual or suitable way, but I prefer to use the vibrators *L* which consist of a plurality of 80 downwardly acting impact members arranged in transverse rows between and spaced apart from the sides of the casing and disposed above the longitudinal edges of the screens and opposite or in the plane 85 of the springs *Q*, as the knockers *i'* loosely or elastically connected by spring arms *j'* and holders *k'* with shafts *l'* which extend through bearings in the end walls *e*, and are oscillated by arms *m'* which are connected 90 together by an adjustable link *n'*, and are connected by a link *o'* to the strap *p'* of an eccentric *S* driven from the shaft *F*. This eccentric has a throw sufficient to cause the knockers to move slightly farther than 95 necessary for them to hit the clamps *R* over and opposite the longitudinal edges of the screens, so that the knockers hit these clamps a suitable percussive or impactive blow, and the elastic bars *j'* yield sufficiently to make 100 up for any additional oscillation of the knocker shafts. The resiliently mounted or spring mounted screen frame may yield slightly under this blow, so that the screen clothing thereon will be jarred by the blow 105 as well as slightly moved thereby. This jar ring will be sufficient to prevent clogging of the screen, and to facilitate downward flow of material thereover.

Leakage between the end walls *e* and the side bars *k* of the screen frame may be prevented in any usual or suitable manner, but I prefer to cast the inner face of the end walls with a pocket *q'*, and to mount on this face and in this pocket a yielding dust bar 110 or plate *T*, which may be clamped against the end wall with an intervening packing strip, or may be sprung or pressed outwardly from this wall in such manner as to bear against the side of the screen frame and prevent leakage at this point, but which is preferably a spring pressed bar slidingly mounted in the pocket as shown.

The inlet *J* is directly above the screens, and preferably consists of two removable deflectors, the one *U* being inclined downwardly and forwardly and resting on and lapping the top of the screen for a suitable distance, and the other *V* being inclined downwardly 120 and rearwardly and terminating a suitable 125

distance above the deflector U to give the necessary clearance for the inlet J, these deflectors being so disposed that feed from either the rear or the front side of the feeder 5 will be directed downwardly and forwardly on to the top of the screen. The deflectors are removable through the feeder casing, and are carried by a cast iron carrier W bolted to the inner face of each end wall e. This 10 carrier has flanges r' projecting inwardly from the end walls to prevent leakage past the ends of the deflectors, which flanges are notched near the bottom to permit the deflector U to pass downwardly, and are provided with a curved wall s' for directing 15 material on to the deflector U. The back of each carrier W is recessed to clear the dust plate T, and the lower corner overlaps, and prevents leakage at, the side edge of the 20 screen, and is recessed or notched to clear the screen.

As shown the feeder or distributor is bodily reversible to bring its hopper at either end. Its casing comprises two cast metal end walls X connected by angle irons t', closed at the top by a sheet iron top wall u' from one extremity to the hopper E, which latter closes the remainder of the top, closed at front and rear by doors v', and removably 25 bolted to the top of the body A. The distributing conveyer K is reversible both in position and drive and extends from end to end of the feeder casing, and beneath the conveyer the feeder has a trough Y flanked 30 on each side of the conveyer by an adjustable feed plate Z, which is mounted to be tilted to the necessary angle to cause the material distributed by the conveyer to flow out of the trough in substantially uniform quantity 35 throughout its length.

My invention provides a feed edge, preferably an adjustable plate at each side of the conveyer, and a clearance or discharge outlet at each side, so that the conveyer may discharge to the front or to the rear as desired, according to the direction that it is driven, thus avoiding the necessity for reversing the feed hopper or for using a left hand conveyer. 40 The trough Y is a plate having upwardly bent edges, and is supported from lugs within the casing D by two transverse angle bars, or is otherwise suitably constructed, and has inclined sides to which the feed plates are applied. The end plates X are formed with correspondingly inclined internal flanges w' for supporting the trough, and feed plates on the lower ends of which flanges are lugs for the angle bars supporting the trough.

The eccentric S has a shoulder against which the eccentric strap y' bears, and on its outer end the eccentric is covered with a dust plate x' which protects it from dirt. The strap is provided with an oil well, and each

of the bearings are likewise provided for lubrication. The bearings y' for the driving shaft F are spaced apart at z' from the wall to permit any dust which may escape from the feed casing along the shaft to fall 70 downwardly instead of entering the bearings.

The feed hopper E is formed with a depending flange a' at each side to prevent material from jumping across from the hopper directly over the feed board, and with a vertical neck b' to direct the feed downwardly on to the conveyer. The legs C are formed with a plurality of holes c' through any of which the bolts d may be passed to support the body A from the legs at the desired angle. Each end piece e is formed with a projecting ear d' which laps the side wall v of the bottom door M, and has a curved edge struck from the center of the pivotal pin t, and the lower edge of the side 80 wall v extends out under the projection d' to prevent leakage beneath the latter at the sides.

The angularity of the screen G is fixed relatively to the body, and its steepness is 90 adjusted by adjusting the entire body until the desired angle for the screen is obtained, but I prefer to construct the bottom M of a greater steepness than that of the screen in order to insure free flow of the screened material, which owing to its fineness is not likely to flow as freely as the coarser material. 95

The posts c' will project in the direction in which it is desired that the yielding frame 100 P shall reciprocate, and are formed with slots g' through which are passed bolts h' in the ends of the frame P, which bolts act as stops to arrest the upward movement of this frame, while permitting it to freely descend when the springs are compressed. Thus the frame P slides up and down on the posts in its movement under the action of the mechanism L, and is abruptly stopped at a predetermined point in its upward 110 movement. The effect of this is to permit the material on it to rise and to jar out of the meshes of the screen any pieces that may have wedged therein.

When an end motion or knock for the 115 screen is desired, this may be attained in any suitable manner, but I prefer to put a cam z' on the lower side of the oscillating arms, and have it run against a roller j' fastened to the adjacent end dust bar T, and passing 120 through slots in the ends e, and to provide springs k' for pressing the screen toward this roller. The roller rides up the bevel of the cam and compresses the spring, and when the roller passes to the opposite side 125 of the cam, the spring presses the screen back until its roller strikes the cam, thus giving it the desired movement and jar transversely of the flowing material. To provide for this end motion, the internal 130

pockets in the ends *e* are preferably deep enough to give the necessary clearance for end motion, and the side dust plates are angle or channel bars sliding in these pockets and having flanges of sufficient width to allow for the desired motion without escaping from the pockets.

The vibration of the screen insures flow of material down it when it is relatively flat, but as the bottom is without vibration, the fine material is liable to stick thereon unless the angle is relatively steep, and to avoid this my invention provides a greater angularity for the bottom wall than for the screen.

In operation, the driving pulley *e* being on either end of the shaft *F*, and the eccentric and arms *m* being on the other end, the feed hopper will be placed at either end 10 of the feeder according to convenience, and the conveyer *K* will be driven in such direction as to propel the material fed through the trough *Y* toward the other end of the machine. The feed board *Z* at the side of the conveyer where the flights are rising will be tilted until the material flows over its edge in a substantially uniform volume from end to end. This will be determined by opening the front or rear door of the feed casing and adjusting the feed board by hand until a satisfactory distribution of material is obtained. If the feed is flowing over the rear board it will fall on the deflector *U*, slide down this on to the screen *G*, 25 and flow over and through the latter, the coarse going to the outlet *I* and the fine to the outlet *II*. If the feed is over the front board *Z* it will fall on to the deflector *V* and slide rearwardly down this until it falls 30 on to the deflector *U*, from which it will slide on to the screen. The screen vibrates the deflector *U*.

At the end of the trough remote from the hopper the trough is usually formed with an opening *t* to permit escape of material which has not been thrown over the feed plate. I provide an inclined deflector *m* here, which preferably consists of the bent down portion of the metal cut from the trough, which is bent at an angle to direct the material falling through this opening obliquely, either back toward the middle of the screen, or laterally toward the front or rear deflector plates, thus preventing such material from flowing down close to the edge of the screen.

If vibration of the screen is desired, the vibrating mechanism *L* will be connected to the screen and adjusted to knock with the desired force. In such case the strikers *i* will pound the screen clamps with equally rapid blows, and the screen will vibrate sufficiently to keep itself clean and to cause the material to flow rapidly. The springs *Q* 65 will yield slightly under this vibration, and

the knocker straps *j* will flex slightly, thus providing for a slight lost motion effect.

To inspect the surface of the screen, one or both doors *l* may be removed. To withdraw or repair any screen frame, the clamps *R* over it may be loosened, and it may be drawn out bodily through the back door *b* by slightly lifting the deflector *U*, or the entire bottom *M* with the screens and screen frames may be oscillated downward by releasing the clamps *p*, and any of the screens may be repaired in place, or may be slid outward, or lifted out and recovered. On re-assembling the screens, the hinged bottom *M* can be closed up and clamped, and the machine is again ready for operation.

Where great steepness is desired for the screen, the body can be adjusted upward and the bolt *d* fastened in one of the upper holes. If less steepness is desired, the body 85 can be connected to one of the lower holes *c* of the legs *C*. The front end of the body will rock on the pin *e* throughout these adjustments without clearing the side walls of the feet *B*, which walls serve to prevent 90 escape of dust at the sides of the separator in all its normal positions.

The front door *a* may be adjusted vertically to permit discharge wholly or partially through the front of the separator, for which purpose it is loosely mounted to slide in the groove *f*, which is duplicated at each end of the part *e*.

For transportation, the parts can be shipped erected as shown, or if desired the body *A* may be folded down between the feet *B*, and the legs *C* can be disconnected from the feet and folded up on top of the feet, whereupon the whole can be crated with great compactness; or where even a closer 100 packing is desired, the feed casing *D* with its inclosed parts can be separated from the body and shipped separately. If desired the casing *A* can be taken apart and shipped in pieces, all the parts being separably connected together to facilitate this.

It will be noted that the angles *t* of the lower corners of the feed casing are so disposed that they form shelves on which the material can build up to seal the joint at the 115 lower edge of the front and rear doors *v*, and thus prevent leakage beneath these, and that the bar *g* is so arranged as to dust can accumulate above it and seal the joint at the bottom of the door *b*, and also that the angle *o* is adapted to collect a body of material to seal the joint between itself and the angle *i* at the front of the body *A*.

It will be seen that my invention provides a screening apparatus which is simple, 125 strong and compact, and which combines easy accessibility with a wide range of adjustment; also that it provides a device which can be driven in either direction without the necessity of disturbing or reversing 130

any of the parts, and one in which the mere shifting of the feed hopper from one end to the other suffices to adapt the machine for receiving feed at either extremity.

5 It will be understood that my invention is not limited to the particular details of construction, combination of parts, or method of operation herein set forth and shown as constituting its preferred form or 10 adaptation, since my improvements can be availed of in whole or in part according to such modifications as circumstances or the judgment of those skilled in the art may dictate, without departing from the spirit 15 of my invention.

When it is desired to jig the screen frame instead of knocking it, I connect the frame by a yielding connection to the oscillating shafts, and provide stops against which it 20 strikes on its upward movement, and I make this movement such that the screen moves both upwardly and forwardly in approaching the stops. In such case I may use spiral springs instead of leaf springs, and extend 25 a bolt through these springs, using the head of the bolt for the stop and connecting the rocker arms to the screen by a link and spring connection, which will yield to supply the desirable lost motion. I may also in 30 such a construction use the knockers, disposing the parts so that as the lifting arm raises the screen the descending arm will strike it, thus combining both a jig and a knocking effect. One such modification is 35 illustrated in Fig. 9, in which the screen frame P'' is supported by spiral springs Q' from the door M at the top and the angle f extending between the sides e at the bottom. Bolts p^3 extending through these springs 40 position the parts, permitting necessary movement of the screen frame P'' . A link Q^3 hinged to the screen frame and to the bar f causes the frame to move rearwardly slightly when it is depressed and stop or 45 shoulder c^3 limits its upward movement.

The oscillating holders k^3 mounted on the shafts l^3 are loosely connected to the screen frame by links m^3 which are hinged to the frame and movably connected to the 50 holders so that when the holders oscillate they will act through the links alternately to depress the frame. The swinging strikers i^3 are here shown as having their arms j^3 hinged to the holders k^3 and yielding 55ly pressed thereagainst by springs n^3 on the links m^3 , which springs provide a yielding connection between the screen frame and the oscillating shafts as well as serving to impel the strikers to swing with the holders 60 k^3 while permitting them to yield if necessary on striking.

While I have herein shown and described the feeder and distributor set forth, the same is not claimed in this application, being the 65 subject matter of claims in my application

Serial No. 82,750 of 1915 filed March 7, 1916
Serial No. 33,464 of 1915 filed June 11, 1915
which is a division of the present application, and Serial No. 33,465 of 1915 filed June 11, 1915, which is a division of a companion application. 70

What I claim is:—

1. In a screening apparatus, a vibrating inclined screen, in combination with an adjustable casing for it having a removable 75 inclined bottom supporting said screen and detachably connected to the casing at its upper end.

2. A vibrating inclined screen, in combination with an adjustable casing for it having a bottom wall of greater inclination than 80 the screen and movable downwardly to give access to the screen.

3. A vibrating inclined screen, in combination with a movable casing for it having a pivoted bottom of greater inclination than 85 and supporting said screen and hinged near its lower part.

4. A movable inclined screen, in combination with a casing for it permitting its downward movement, and oscillating striking means comprising impact strikers above, acting toward, and independent of said screen and within said casing and between its top wall and said screen for vibrating the latter. 90

5. A vibrating inclined screen and means positioning it, in combination with striking means comprising spring impelled swinging hammers above, acting on, and independent of said screen for vibrating it, a revolving 100 shaft for driving said striking means, and a driving connection between said shaft and said means operating the latter from the former.

6. A movable inclined screen, in combination with a casing in which it is downwardly movable, springs within said casing supporting said screen therein, and an oscillating shaft within said casing above said screen, means operated by said shaft and comprising swinging impact hammers acting on the upper side of said screen for vibrating said screen, and a cover for said casing above and inclosing said shaft and said means. 105

7. The combination with an inclined vibrating screen and a stationary casing inclosing it, of means closing the space between the edge of the screen and the side walls of the casing, consisting of a yielding 110 plate carried by said walls and pressing against the edge of the screen. 115

8. A movable inclined screen, in combination with a casing for it having a movably mounted yielding screen frame having a plurality of parallel screen tracks disposed in a common plane, removable screen members slidingly fitting said tracks and clamped thereto and carried by said frame, and means for vibrating said frame. 125

9. The combination with an inclined removable screen, of spring impelled impact strikers or hammers above and acting on said screen for imparting percussive movements thereto.
10. In a screening apparatus, the casing, an inclined spring supported screen therein, oscillating shafts within said casing, a distributor above said casing, a driving shaft therefor, a connection between said oscillating shafts and said driving shaft for oscillating the former, and yieldingly impelled swinging knockers above said screen operated by said oscillating shaft.
11. In a separator, the combination with a casing and with one or more inclined screens removably mounted thereon, of a jarring mechanism for vibrating the screen clothing, an inclined removable floor or bottom beneath the said screen or screens which latter may be inserted in place or removed when said removable floor or bottom is off.
12. In a separator, the combination with one or more inclined removable screens, of a casing inclosing said screen or screens, said casing comprising an inclined floor or bottom beneath said screen or screens and which is arranged at a steeper angle than the said screen or screens, said bottom having a door or removable part which, when opened or removed, affords access to said screen or screens and permits of their convenient removal.
13. In a separator, the combination with a frame or casing and one or more inclined screens removably mounted thereon each comprising a rectangular frame and screen clothing stretched on said frame, of means beneath the inclined sides of said frame or frames resiliently supporting the latter at the downwardly extending edges thereof, and jarring mechanism above said means acting percussively downwardly toward said screen in the vertical plane of said resilient supporting means.
14. In a separator, the combination with a frame or casing, of a plurality of removable inclined screens therein each comprising a rectangular frame and screen clothing stretched thereon, resilient supports for the adjacent edges of two of said screens, and means for percussively jarring said screens.
15. In a separator, the combination with a frame or casing, and a plurality of removable inclined screens therein each comprising a rectangular frame and screen clothing stretched thereon, resilient means supporting adjacent edges of two of said screens, and means opposite adjacent edges of two of said screens for jarring them.
16. In a separator, the combination with a frame or casing, of two or more removable inclined screens disposed in parallelism and each comprising a rectangular screen frame and screen clothing stretched thereon, of means opposite adjacent edges of two of said screens for jarring them.
17. In a separator, the combination with a frame or casing and a removable inclined screen thereon comprising a rectangular screen frame and wire mesh clothing stretched thereon, of jarring mechanism between, remote from, and spaced apart from, the sides of said casing and opposite and acting on the edge of said frame, for percussively jarring said screen at a point or points intermediate of the sides of said casing.
18. In a separator, the combination with a frame or casing, and a plurality of removable inclined screens therein each comprising a rectangular screen frame and screen clothing stretched thereon, and disposed in parallelism in said casing with their edges adjacent one to the next, of means opposite the adjacent edges of two of said screens for preventing leakage between them, means resiliently supporting said screens, and means for percussively jarring said screens.
19. In a separator, the combination with a frame or casing, and a removable inclined screen therein, of a plurality of springs between, remote from, and spaced apart from, the sides of said frame or casing, and disposed in a row transversely of said casing, beneath said screen and resiliently supporting the latter, and a plurality of jarring devices between, remote from, and spaced apart from, the sides of said frame or casing for percussively jarring said screen disposed in a row transversely of said casing opposite said row of springs and acting percussively toward said screen in opposition to the stress of said springs.
20. In a separator, the combination with a frame or casing, and a plurality of removable inclined screens therein each comprising a rectangular frame and screen clothing stretched thereon, and disposed in parallelism in said casing, of a plurality of parallel bars or supports mounted in said casing opposite the adjacent edges of said screens, springs mounted on said supports and resiliently sustaining the edges of said screens and exerting an upward and forward stress for resiliently supporting the edges of said screens, and jarring mechanism acting toward the edges of said screens percussively reversely of the stress of said springs for jarring said screen clothing.
21. In a separator, the combination with a frame or casing, of a removable inclined screen therein comprising a resiliently mounted removable rectangular oblong screen frame and screen clothing stretched on the upper side thereof, and means for percussively jarring said screen comprising a plurality of impact members spaced apart longitudinally of, and opposite and acting

- 1 toward the upper side of, the longitudinal edge of said frame at spaced points intermediate of its extremities.
22. In a separator, the combination with 5 a resiliently mounted removable inclined screen comprising a resilient frame or support and screen clothing mounted on the top thereof, and means for percussively jarring said screen, of a casing within which said 10 screen is resiliently mounted having an inclined bottom wall of steeper inclination than said screen.
23. In screening apparatus, a resiliently mounted removable inclined screen, in combination with a casing in which it is enclosed, and downwardly acting jarring 15 means above said screen for vibrating it, said casing having a detachable bottom wall spaced below and of greater inclination than 20 the screen, and means resiliently sustaining said screen above said bottom wall.
24. An inclined resiliently mounted removable screen, in combination with means for jarring said screen, and a casing inclosing 25 it having a hinged bottom wall hinged to its lower part, and means resiliently sustaining said screen above said wall.
25. A resiliently mounted removable inclined screen, in combination with an adjustable casing inclosing it, means for adjusting the angularity of said casing, resilient means supporting the screen in said casing, stops or abutments for arresting upward movement of said screen in said casing, and means for downwardly jarring said 30 screen.
26. In a separator, the combination with a resiliently mounted removable inclined screen, and means for percussively jarring 35 it, of a casing inclosing said screen and having an inclined wall or bottom beneath the latter, and means for supporting said screen within said casing below and opposite the edges of said screen and above and spaced apart from said wall or bottom to afford a 40 passage or space above the latter and below said means.
27. In a separator, the combination with a resiliently mounted inclined removable 45 screen, and means for percussively jarring it, of a casing for said screen having side walls and a bottom wall inclosing said screen, and supporting means intermediate of, remote from, and spaced apart from, 50 said side walls, and below said screen for resiliently supporting it intermediate of said side walls.
28. In a separator, the combination with a resiliently mounted removable inclined 55 screen, and means for jarring it, of a casing for said screen having a bottom and side walls, a bar or member spaced above said bottom and extending transversely of said casing between said side walls below and 60 sustaining said screen intermediate of said
- side walls and on which said screen is resiliently mounted.
29. In a separator, the combination with a removable resiliently mounted inclined screen, and means for jarring it, of a main 70 frame or casing on which said screen is mounted, sustaining means within and disposed transversely of said frame or casing and below and sustaining said screen intermediate of its side edges, and means 75 above said screen for preventing leakage of material over the top edge thereof spaced apart from said sustaining means and affording a space or chamber above the latter for receiving the upper edge of said screen. 80
30. In a separator, the combination with a removable inclined screen having a downwardly and rearwardly extending part or member at the under side of its upper edge, of a frame or casing on which said screen is 85 removably mounted having side walls at the side edges of the latter, and means mounted on said frame or casing intermediate of said side walls having an upwardly and forwardly extending part or member beneath 90 and engaging said downwardly extending part or member for sustaining said screen.
31. In a separator, a removable inclined screen, in combination with a casing therefor having walls inclosing said screen, means 95 beneath the edge of said screen, and between, remote from, and spaced apart from, the side walls of said casing, resiliently supporting said screen at a point or points intermediate of said side walls, and means affording a stop or abutment for limiting upward movement of said screen. 100
32. In a separator, the combination with a removable inclined screen, and means for jarring it, of a frame or casing on which said screen is resiliently mounted, a transverse bar or member mounted on said frame or casing beneath and sustaining the edge of said screen, and springs resiliently supporting said screen. 105
33. In a separator, the combination with a resiliently mounted removable inclined screen, and a frame or casing on which it is mounted, of means extending transversely of said frame or casing at the upper edge of said screen for preventing leakage of material over said edge, and resilient means below the upper edge of said screen for sustaining said screen, said upper means and said resilient means spaced apart to afford between them a recess or chamber for receiving the upper edge of said screen. 115
34. In a separator, the combination with a removable inclined screen, and a frame or casing on which it is mounted, a bar or member extending transversely of said frame or casing beneath and sustaining said screen, and a spring or springs resiliently supporting said screen. 120
35. In a separator, the combination with 125

- a removable inclined screen, and a casing having side and bottom walls inclosing said screen, of means below the lower part of said screen and sustaining the latter, spaced above the bottom wall of said casing and affording a space or passage beneath said means, and a spring or springs resiliently supporting said screen.
36. In a separator, a removable inclined screen, and a casing therefor comprising a bottom wall, in combination with a bar or member mounted on said casing below and spaced apart from said screen and above and spaced apart from said wall, and a spring or springs between said screen and said bar or member resiliently supporting the former from the latter.
37. In a separator, a removable inclined screen comprising a rectangular screen frame and a screen clothing stretched on the upper side thereof, and a frame or casing on which it is resiliently mounted, in combination with a bar or member mounted on the edge of the top face of said screen clothing, an impact member above and opposite the edge of said screen and acting impactively on said bar or member for jarring said screen, and means sustaining said screen in said casing.
38. In a separator, the combination with a removable inclined screen, and a casing on which it is removably mounted, of means extending transversely of said casing above the upper edge of said screen for preventing leakage over such edge, and means at the side edges of said screen affording a recess above and for receiving such edges for preventing leakage past the latter.
39. In a separator, the combination with a resiliently mounted removable inclined screen, of a frame or casing on which said screen is mounted, and jarring mechanism acting on the side edges of said screen, comprising impact strikers percussively jarring said screen.
40. In a separator, the combination with a removable resiliently mounted inclined screen comprising a rectangular frame and screen clothing mounted thereon, of a plurality of springs disposed in a downwardly extending row opposite and acting resiliently toward said screen clothing, and a plurality of impactive jarring devices disposed in a downwardly extending row in the vertical plane of said row of springs and opposite said screen clothing and acting percussively toward said screen clothing in the vertical plane of the stress of said springs.
41. In a separator, the combination with a resiliently mounted removable inclined screen, of a casing having an inclined bottom wall and in which said screen is removably mounted, a bar or member beneath said screen and extending transversely of said casing, spaced apart from said bottom
- wall to afford an outlet for fine material beneath it, and spaced apart from the front of said casing to afford an outlet for coarse material in front of it, and sustaining said screen to permit resilient vibration of the latter, and means above said screen for impactively jarring it.
42. In a separator, the combination with a resilient removable inclined screen, of a casing in which said screen is mounted having an inclined bottom wall and side walls, means within said casing intermediate of said side walls and spaced apart from said bottom wall beneath and sustaining the upper edge of said screen, and affording a passage beneath said means and above said bottom wall past the upper edge of said screen for communicating with the space beneath the latter.
43. In a separator, a removable inclined screen, in combination with a casing therefor having side and bottom walls and means disposed transversely of said casing below and spaced apart from the upper edge of said screen and affording a space beneath the latter, and springs sustaining said screen from said means.
44. In a separator, a plurality of removable inclined screens, and a frame or casing on which said screens are mounted, in combination with bars or members extending transversely of said casing and spaced apart from the bottom wall thereof, and sustaining said screens.
45. In a separator, the combination with a plurality of removable inclined screens, and a casing on which said screens are mounted having side and bottom walls, of a bar or member beneath the adjacent edges of two of said screens and sustaining them, spaced above said bottom wall to afford a passage above the latter.
46. In a separator, the combination with a plurality of removable inclined screens, and a casing on which said screens are mounted having side walls and an inclined bottom wall, of transverse bars or members mounted in said casing beneath and spaced apart from said screens for sustaining the latter, and springs resiliently sustaining said screens from said bars.
47. In a separator, the combination with a removable inclined screen, of a casing in which said screen is resiliently mounted having side walls inclosing said screen, bars or angles mounted against the inner side walls of said casing and having inwardly extending flanges beneath and sustaining said screen at the sides of said casing, and means resiliently sustaining said screen intermediate of the sides of said casing.
48. In a separator, the combination with a resiliently mounted removable inclined screen, and a casing on which said screen is mounted, of bars or angles mounted within

said casing below and sustaining said screen, strips or plates removably mounted above said bars or angles and on the top of said screen, means supporting said bars or angles, and means above and acting on said strips or plates for percussively jarring said screen.

In witness whereof, I have hereunto signed my name in the presence of two subscribing witnesses.

GEORGE HOLT FRASER.

Witnesses:

FRED'WHITE,

THOMAS F. WALLACE.
